UNITED STATES PATENT OFFICE.

JOSE ALCARAZ, OF NEW YORK, N. Y.

JUGGLING TOY.

Application filed January 4, 1924. Serial No. 684,281.

To all whom it may concern:

Be it known that I, JOSE ALCARAZ, a citizen of Mexico, residing at New York, in the county of New York and State of New York, have invented certain new and useful Improvements in Juggling Toys, of which the following is a specification.

This invention has for its main object to provide a type of juggling toy for children and others, which is both instructive and entertaining as it requires practice to become adept in its use, as after short practice the trick which appears difficult at first, may be readily accomplished.

Another object is to provide an article as mentioned and comprising a handle bar used as a spear, and a free swinging member, flexibly connected to the spear by a cord, the trick of this toy being to swing the last-named member and catch the same upon the spear.

These and other objects will become apparent in the description below, in which characters of reference refer to like-named parts in the drawing.

Referring briefly to the drawing, Figure 1 is an illustrative perspective view showing the swinging member in various positions and the spear poised for a catch.

Figure 2 is an elevational view showing a modified type of swinging member poised upon the spear, the swinging member being shown in section to illustrate the construction thereof.

Figure 3 is an illustrative view showing the toy in its initial position preparatory to the performance of the trick.

Referring in detail to the drawing, the numeral 1 indicates a swinging member, in this case a drum but its outline may be of any design desired. In Figures 2 and 3 a spheroid swinging member 2 is illustrated. Both types of swinging members have longitudinal circular channels 3 passing axially thru the greater portion of the body of the swinging members. These circular channels communicate with a smaller opening at their opposite ends, the opening being indicated by the numeral 4. A flexible cord 5 of suitable length has one of its ends formed into a knot 6 after said end has been slipped thru the

opening 4. The opposite end of the cord is then twisted around a spear handle 7, and is secured to said handle intermediate its length in a circular depression 8. The outline of the handle is curved into any ornamental shape desired and the base 9 may be used to support the same in vertical position when the toy is not being used. At the upper end of the handle a stud 10 is provided which is tapered thru a portion of its length, said stud being adapted to be easily slipped into the channel 3 of its respective swinging member.

The swinging member shown in Figure 1 is cylindrical in shape having its outer peripheral edges formed into flat tapering bands 11 and the surface between these bands is spherical in shape, said portion being indicated by the numeral 12.

In using the toy to perform the trick, the handle is grasped in the palm of the hand with the stud 10 pointing upwardly. When in this position the swinging member hangs suspended from the cord 5 as illustrated in full lines in Figure 3. The suspended swinging member 1 or 2 is then oscillated to and fro until the inertia carries the same to horizontal position. Until this time the distance between the handle and swinging member 80 remains fixed by the cord 5, which is until this time taut. As the swinging member is lifted above the horizontal plane the hand which holds the handle is moved into closer relation with the swinging member thereby permitting the latter to rotate. As the swinging member travels from the horizontal to the vertical plane, the same will rotate about its axis. As the swinging member rotates to the position where the channel 3 is nearly in a vertical plane and mutually adjacent the stud 10 the handle is thrust toward the swinging member, so that said stud 10 is inserted into the channel 3. At an initial trial the trick appears difficult but with some little practice a person becomes adept and can usually cause the swinging member to readily engage the stud of the handle member.

I claim:

A juggling toy comprising a swinging cylindrical body having a cylindrical channel

100

2
passing axially therethru, the channel being
larger at one end, a spherical surface encir-
cling the body intermediate its length, a
knotted cord passing thru the restricted end
5 of said channel, a handle, the opposite end
of said cord being secured to said handle, a
stud on the end of said handle, said stud

having a blunt end, the stud extending lon-
gitudinally from the handle, said stud being
partly tapered lengthwise, and a base on the ¹⁰
opposite end of said handle.

In testimony whereof I affix my signature.

JOSE ALCARAZ.
